UNITED STATES PATENT OFFICE.

JOHN SCHLUTTER, OF BALTIMORE, MARYLAND.

PHONOGRAPH.

Application filed September 10, 1925. Serial No. 55,462.

This invention has reference to a phonograph by which sound is reproduced and transmitted from the record through the turn-table to a diaphragm, amplified by a vibratory member in the nature of a sounding board, and then broadcast laterally from beneath the latter in all directions.

The general object of the invention is to provide a device which will reproduce and amplify the sound without affecting its quality, or distorting the sound waves, and without the accompaniment of any scratching noise.

In phonographs as usually constructed, the record rests on a turntable, which has a substantially rigid support, while the stylus is supported on a spring arm, and the tone arm and stylus have a comparatively free movement, independent of the vibrations of the diaphragm. In my construction, the stylus is carried by a comparatively stiff arm, while the diaphragm holder is rigidly secured to a rotatable support, and the turntable on which the record rests is resiliently supported by said rotatable support above the diaphragm, and is free to move up and down or sidewise so as to lessen the friction between the record and the stylus, thereby eliminating the scratching noise, while the reproduced sound waves are transmitted through the diaphragm and underneath an annular amplifier or sounding board, and are broadcast laterally from all sides.

The specific construction of the invention and the principles of its operation will be more clearly understood from the following detailed description taken in connection with the accompanying drawing, which illustrates one embodiment thereof.

40 In the drawing:

Figure 1 is a central vertical section of the invention.

Figure 2 is a section taken approximately on the line 2—2 of Figure 1, parts of the record and turntable being broken away in order to better show the construction.

rim of the cup-shaped member 10. The center of the plate 11 is formed with a downwardly projecting boss or socket 13, having a diametric slot 14 adapted to receive a pin 15, which is disposed transversely of the shaft 9 and causes the plate to rotate therewith.

The upper surface of the plate 11 is formed with three or more upwardly projecting lugs 16 to which is secured an annular amplifying disk or sounding board, preferably composed of fiber. A diaphragm holder 18 is disposed within the amplifying disk 17, and is formed with downwardly projecting lugs or feet 19 which are secured to the plate 11. A diaphragm 20 is secured within the holder 18 between an inwardly projecting flange 21 and a removable annular plate 22. 65 70 75

A turntable 23, preferably of aluminum, is secured to lugs 24 formed at the outer ends of spider arms 25, which are resiliently supported by coil springs 26 from the plate 11. The spider is formed with a central hub 27, which is connected to the center of the diaphragm 20 by a pin 28. The turntable 23 is formed with a central upwardly projecting stud 29, which fits into the hole in the record 30, and the upper portion of the turntable is provided with a felt facing 31 on which the record rests. 80 85

A pedestal 32 is secured to the shelf 7 at one side of the plate 11, and is provided at its upper end with a pivot stud 33 on which 90 an arm 34 is mounted. Arms 35 are mounted for vertical swinging movement on the outer end of the arm 34, and carry a head 36 in which the stylus 37 is secured.

From the foregoing description, it will be noted that the stylus is not supported by a spring arm, but is nevertheless free to follow the groove in the record, while the record itself is resiliently supported, and is free to move up and down or sidewise, so as to lessen the friction between the stylus and the record, and to eliminate the scratching noise which would otherwise be developed. The reproduced sound waves, caused by the vibration of the record as the stylus travels along the groove, are transmitted through the turntable 23 and spider arms 25 to the diaphragm 20. From the diaphragm, the sound waves pass outwardly beneath the amplifying disk 17, and are broadcast laterally from all sides without interference, like the waves produced by dropping a pebble.

ble into water. In a phonograph constructed in the usual manner, the whole tone arm is vibrated, or jarred, independently of the vibrations of the diaphragm, thus injuring the quality of the tone. The waves are also distorted by the curves in the tone arm, and are emitted, for the most part, in one direction, while with the present construction, the sound is broadcast from all sides equally without distortion or interference.

While I have shown and described in detail the construction which is at present deemed the most suitable for the purpose, it is obvious that many modifications may be made therein without any material departure from the essential features of the invention as expressed in the appended claims.

What is claimed is:

1. In a phonograph, a rotatable horizontally disposed plate, a turntable supported above and in spaced relation to the plate, a diaphragm between the turntable and plate, and means for transmitting vibrations from a record carried by the turntable to said diaphragm.
2. In a phonograph, a rotatable horizontally disposed plate, a diaphragm holder secured to the upper side of the plate, a diaphragm in said holder, a turntable resiliently supported from said plate above the diaphragm, and means connecting the turntable to the diaphragm.
3. In a phonograph, a rotatable horizontally disposed plate, a turntable supported above and in spaced relation to the plate, a diaphragm between the turntable and plate, and a spider secured to the under side of the turntable and having a central hub connected to the diaphragm.
4. In a phonograph, a rotatable horizontally disposed plate, a turntable supported above and in spaced relation to the plate, a diaphragm holder between the turntable and plate, a diaphragm secured in said holder, means for transmitting vibrations from a record carried by the turntable to the diaphragm, and an annular amplifying disk surrounding the diaphragm holder and spaced from said plate.
5. In a phonograph, a rotatable horizontally disposed plate, a diaphragm holder secured to the upper side of the plate, a diaphragm secured in said holder, a turntable resiliently supported by said plate above the diaphragm, means connecting the turntable to the diaphragm, and an annular amplifying disk surrounding the diaphragm holder and spaced from said plate.
6. In a phonograph, a rotatable horizontally disposed plate, a turntable supported above and in spaced relation to the plate, a diaphragm holder between the turntable and plate, a diaphragm secured within the holder, a spider secured to the turntable and having a central hub connected to the

diaphragm, and an annular amplifying disk surrounding the diaphragm holder and spaced from said plate.

7. In a phonograph, a rotatable horizontally disposed plate, a diaphragm holder having feet secured to the upper side of said plate so that the holder is spaced therefrom, a diaphragm secured within said holder, a turntable supported by said plate above the diaphragm, a connection between the turntable and diaphragm, lugs projecting upwardly from the plate outside of the diaphragm holder, and an annular amplifying disk secured on said lugs and parallel to the upper face of said plate.

8. In a phonograph, a rotatable horizontally disposed plate, a diaphragm holder having feet secured to the upper side of said plate so that the holder is spaced therefrom, a diaphragm secured within said holder, a spider having a central hub connected to the diaphragm and having radial arms, coil springs underneath said arms for supporting the spider from said plate, a turntable secured to and supported by the outer ends of the spider arms, lugs projecting upwardly from the plate outside of the diaphragm holder, and an annular amplifying disk secured on said lugs and parallel to the upper face of said plate.

9. In a phonograph, a rotatable horizontally disposed plate, a diaphragm holder having feet secured to the upper side of said plate so that the holder is spaced therefrom, a diaphragm secured within said holder, a spider resiliently supported by the plate above the diaphragm and having a central hub connected with said diaphragm, upwardly disposed lugs at the outer ends of the arms, a turntable supported by and secured to said lugs in spaced relation to the spider, and an annular amplifying disk surrounding the diaphragm holder and spaced from said plate.

10. In a phonograph, a motor having an upwardly projecting vertical shaft, a cup-shaped member secured to the shaft, a pin secured transversely of the upper end of the shaft, a plate having a central downwardly projecting socket receiving the end of the shaft and provided with a diametric slot for receiving said pin, an annular flange formed on the under side of said plate and adapted to rest on the rim of the cup-shaped member, a diaphragm holder supported by said plate and containing a diaphragm, a turntable supported by said plate above the diaphragm, and means for transmitting vibrations from a record carried by the turntable to said diaphragm.

In testimony, that I claim the foregoing as my own, I have hereto affixed my signature.

JOHN SCHLUTTER.
